HOLDER FOR WRITING PARAPHERNALIA

Emanuel R. Posnack, New York, N. Y.

Application March 21, 1939, Serial No. 263,105

16 Claims. (Cl. 281—1)

This invention relates to holders for writing paraphernalia and the like, such as paper pads, cards, letters, pens and pencils, and particularly to devices of this category in the form of stands 5 adapted for convenient placement upon desks and tables.

Although there are many desk appliances for holding various writing appurtenances, they are generally not provided with means, forming part 10 of a simple and unitary structure, adapted to conveniently receive and releasably retain there-in a considerable quantity of desk paraphernalia and at the same time present a readily accessible and convenient writing surface for note taking. 15

It is hence primarily within the contemplation of this invention to provide just such a device, of presentable and ornamental appearance, economical to fabricate, and capable of quickly and readily receiving, and retaining in accessible positions, a pad of writing paper, pens, pencils, 20 scrap paper such as those containing notes thereon, envelopes, cards and the like.

Most commonly used pad holders are either of the "flat" type where the writing surface of the 25 exposed sheet is unobstructed but where the detachment of each sheet must be effected by tearing it off the holder,—or of the "loose sheet" type where a pad of unattached sheets is positioned in a receptacle provided with peripheral retaining walls. In this latter type of holder, the lateral peripheral walls thereof, in order to serve as 30 retaining members, must be of greater height than the thickness of the pad, and consequently constitute obstructions and encumbrances to 35 convenient note-taking on the pad; and furthermore, the said walls make it difficult to reach the edge of the top sheet, and particularly of an underlying sheet, for its removal from the holder. It is also to overcome these shortcomings that I 40 seek to accomplish with my invention, an objective which I attain by combining the advantages of both of the aforesaid types of holders, and eliminating their disadvantages. And in this aspect of my invention, it is an object to provide 45 means for retaining a "loose" pad in such manner as to at all times present an unobstructed writing surface, and at the same time permit a ready removal of either the top or an underlying sheet of the pad without any tearing or other mutilation thereof.

Another object of this invention is to enable a 50 pad of paper to be releasably held in place by a predetermined yieldable pressing action, and in such manner as to enable any selected sheet of the pad to be removed without materially af-

fecting the position or disposition of the other sheets. And in this aspect of my invention it is another object to effect an adjustment of the yieldable pressure applied to the pad.

It is also an object of this invention to enable 5 pads of various widths to be readily accommodated for immediate use.

Other objects, features and advantages will appear from the drawings and the description hereinafter given.

10 Referring to the drawings,

Figure 1 is a perspective view of a preferred form of my invention, a pad and certain writing paraphernalia being shown held therein.

Figure 2 is a rear view of a form of my invention similar to that of Figure 1, illustrating a pressure-adjusting arrangement and showing, in dot-dash lines, a position of the parts adapted for applying a comparatively reduced pressure upon a pad.

Figure 3 is a fragmentary side view of the device of Figure 2.

Figure 4 is a fragmentary perspective of a somewhat modified form of my invention.

Figure 5 is a perspective view of a modification 25 of my invention.

Figure 6 is a fragmentary section of Figure 5 taken substantially along line 6—6, and

Figure 7 is another modification of my invention, a pencil being shown retained in place.

As shown in the drawings, and particularly Figures 1 to 3 thereof, the main elements constituting my holder are a base 10, preferably although not necessarily with an inclined upper surface, and resilient clamping means comprising an upright or supporting member 11 suitably joined to the base and a clamp member or holding element 12 suitably attached to the said upright. In the particular form illustrated the members 11 and 12 are shown connected by rivets 35 13, although they can, within the contemplation of this invention, be spot-welded, clamped or otherwise secured together; and the upright 11 is shown secured to rear surface 14 of the base by screws 15, but it is likewise to be understood that 40 its joinder to the base can be otherwise effected, and by other fastenings, depending upon whether the base is solid or of sheet-metal stamping, or whether it is a separate piece or integral with the upright. It is also preferred that both members 45 11 and 12 be of resilient sheet-metal or other material in sheet or wire form, although my invention could also be operative with only one of such members resilient, as will become evident from the description hereinafter given.

In the specific embodiment of my invention disclosed in the drawings, the members 11 and 12 contain curled portions 16, 17 and 18, the portions 16 and 17 at the upper regions of said members being of spiral formation terminating in coiled loops 19 and 20. The spiral-like portions 16 and 17 are so rolled as to provide spaces 21 and 22, respectively, between the curved walls thereof and the adjacent portion of the upright 10 11, as well as space 23 between the spiral-like portion 16 and the adjacent uncurled portion of the member 12,—these spaces being of gradually decreasing proportions to enable them to receive papers and the like therein for frictional 15 engagement with the walls thereof, as will hereinafter appear. The loops 19 and 20 are preferably off-center within their respective spiral formations, and these together with loop 18 are proportioned to receive therein pens and pencils, as 20 indicated in Figure 1.

The thickness of the base 10 and the relative proportions and positions of members 11 and 12 with respect to each other are such that when the said three main parts are assembled together, the lowermost portion 24 of the pad holder 12 will be adapted for pressing engagement with a pad, such as 25, positioned upon the base 10, thereby exerting a yieldable pressure thereagainst. In accordance with the preferred design 30 of the member 12, the said lower portion 24 thereof is of comparatively flat configuration, thereby presenting not only an extended undersurface for engagement with the pad, but also an equally extended upper surface for accommodating paper or other appurtenances thereon. It is also preferred that the parts be so proportioned that portion 24 is engageable with the base proper, thereby being effective as a pad holder regardless of the thickness of the pad,—even 40 up to the last sheet. For best results members 11 and 12 should both be of resilient properties; but if cost, manufacturing or design requirements demand it, one of said members may be relatively rigid inasmuch as the assembled unit 45 of both members will constitute a resilient construction even if only one of said members is of substantial resilient properties.

It will be noted that in the preferred form of my invention illustrated, the rear wall 14 of the 50 base is inclined upwardly and forwardly, thereby serving a two-fold purpose, that of maintaining the rearwardly curved upright 11 in a substantially vertical position, and also that of causing the contacting portion 24 of member 12 55 to be more forwardly disposed and hence exert greater pressure against the base than would be the case if the wall 14 were of less inclination. The illustrated embodiment of my invention also shows the spirals 16 and 17 as being rolled in opposite directions, thereby keeping papers operationally positioned in spaces 21 and 22 from interfering with each other, and also allowing the rear side of the device to be effectively utilized. It is understood, however, that the spiral 19 can 60 also be forwardly disposed, or can be entirely eliminated, all within the scope of this invention.

By referring to Figure 1, it will be readily seen that the device of my invention has both 70 utilitarian and aesthetic features. The pad 25 is conveniently located on the base 10, and is held yieldably clamped thereagainst by the lower portion of member 12. The entire pad is unobstructed, and conveniently and readily accessible for 75 writing. To remove the top sheet, all that need

be done is to withdraw it by a quick and sharp motion; and in the same manner can any intermediate sheet be withdrawn. In neither case need any of the other sheets in the pad be disturbed, inasmuch as the member 12 is constantly exerting a downward pressure thereagainst; and it is of course obvious that every withdrawn sheet is intact and unmutilated.

A removed sheet, such as 26, containing any notes thereon needed for ready reference, can 10 be easily and quickly inserted in space 21 and releasably held at the rear of the device until needed; or it can be inserted in spaces 22, 23 or 27, as are the sheets 28 and 29. It is also apparent that letters, envelopes, cards and other 15 papers can be similarly conveniently accommodated. A number of business cards, or a calendar, can be inserted in the region of the sheet 29; and a number of sheets can likewise simultaneously be inserted within each of the 20 spaces 21, 22 and 23,—especially when the walls forming such spaces are of resilient construction.

And it will also be noted that writing implements like the pen and pencil 30 and 31 can be conveniently held in the loops 18, 19 and 20,—or 25 may also be positioned upon the upper surface of portion 24 of the member 12, or within the space 32 formed by the base 10 and two members 11 and 12.

In Figures 2 and 3 is shown an adjustable 30 arrangement for varying the effective pressure exerted by clamp member 12. The upright 11 is provided at the lower region thereof with vertically disposed slots 33 through which extend the shanks of the screws 15. By loosening these 35 screws, the upright 11 can be raised and lowered, within the limits of the slots, to cause a corresponding movement of the member 12. If the members are raised, the lower portion 24 of member 12 will be moved substantially to the 40 position indicated by dot-dash lines, where it obviously will exert less pressure against the pad than when in the full line position; and of course a reverse movement will increase the pressure.

It is apparent that this device is not limited 45 to any one size of pad, as pads of either greater or lesser widths than the width of member 12 can be readily accommodated for immediate use. Where, however, it is desired to limit the width of the pad to be employed, the modification of 50 Figure 4 can be used. In this figure, the lateral sides of the base 10a are shown provided with strips 34 which extend upwardly for at least the distance of uppermost level of the pad to be employed. These strips serve to hold the loose 55 sheets in the pad against lateral movement, co-operating with the base and member 12a for holding the pad in place, and not interfering in the slightest with the effectiveness of the device for its intended purposes.

In the modification shown in Figure 5, the base 35 and the upright or supporting member 36 are integral with each other, forming a single unitary member. The resilient clamp member 37 is attached to and supported by the member 36 through the medium of prong means, preferably in the form of prong elements 38 extending 60 forwardly from the member 36 through the apertures 39 in the clamp member 37. It is apparent that the prongs 38 can be easily pressed out of 70 the body of the upright, and can be so proportioned as to be readily insertable through said holes 39. Inasmuch as the lower portion 40 of member 37 is in yieldable engagement with the base, it will be constantly urged upwardly 75

in the direction of arrow A (Fig. 6) so that the lowermost wall 41 of each of the apertures 39 will be in abutting engagement with the under-side of the corresponding prong element 38. It is preferred that wall 36 be forwardly inclined, so that the clamp member 37 will be yieldably urged thereagainst, as well as against the prongs 38 as aforesaid. Obviously the lip 42, being downwardly directed, will serve to hold the clamp 37 from being displaced out of its operative position.

With the above-described construction, it is apparent that spot-welding or riveting can be dispensed with, inasmuch as clamp member 37 can be readily assembled upon the supporting member 36 by merely pressing it over the said prong elements and into the position illustrated in Figures 5 and 6. Due to its resiliency, the member 37 can be compressed or contracted during the assembling operation, if necessary, to enable this operation to be made readily effected. And once the parts are assembled, they will be firmly held together due to the constant stress the resilient member 37 is subjected to because of its yieldable engagement with base 35. It is of course understood that instead of having the prong elements integral with the supporting member 36, they can obviously be a part of clamp element 37 and extending rearwardly through suitable apertures in the supporting member,—all within the obvious scope of this invention.

It is preferred, in this modification of my invention, that the supporting member 36 be of substantially stiff and non-resilient construction, so that the combination of supporting member 36 and the base 35 can be readily stamped out of a single sheet of metal of uniform properties. The non-resiliency of supporting member 36 will not adversely affect the utility of this device, inasmuch as the resiliency of member 37 will enable papers to be readily slipped into the space 43 between the coiled portion 44 of member 37 and the upright wall of member 36 adjacent thereto. In other respects, the device of Figure 5 is similar in function and operation to that of Figure 1, in that pencils or other writing paraphernalia can be inserted within the looped portions 45 and 46, and a suitable pad can be inserted below the lower coil 47. It will also be observed that the juncture of members 35 and 36 comprises the depressed portion 48 which serves a twofold purpose, in that it is adapted to receive therein a pencil or other suitable writing implement, and it serves the further purpose of elevating the rear portion of the device so as to impart an inclination to the base suitable for convenient writing purposes.

Figure 7 illustrates a modification substantially similar to the structure of Figure 6, except that instead of a continuous sheet metal clamp member, two spring wires 49 are employed, these being suitably attached to the supporting member 50 at regions 51. The upper coils 52 of these wires contain the looped portions 53 therein for supporting a pencil 54. The said resilient wires 49 are also adapted to receive and frictionally hold therein papers inserted within the spaces 55 which are analogous to the space 23 of Figure 4; and likewise papers can be inserted between the coiled portions 52 and the upright 50 to be frictionally retained in place. The lowermost coils 56 are adapted to support a pencil inserted therethrough, and also to frictionally retain an underlying pad, in a manner similar to that described with reference to the modifications hereinabove referred to.

Not only do the several devices of my invention enable its various objectives to be readily attained, but they are also so constructed as to enable them to be easily and economically fabricated from a few sheet-metal stampings, wire or other inexpensive and ornamental materials. And in addition to being useful and capable of economical manufacture, they are all of such presentable appearance as to render any of them of aesthetic and ornamental value on a desk or table either at home or in an office.

It is of course understood that the various embodiments above-described and shown in the drawings are illustrative of my invention and not employed by way of limitation, inasmuch as numerous changes and modifications may be made within the scope of the appended claims without departing from the spirit of this invention.

What I claim is:

1. A holder of the character described comprising a base adapted to accommodate thereon a pad, and yieldable clamping means supported by the base and associated with the rear portion thereof, said clamping means being adapted for pressing engagement with the rear portion of the said pad to yieldably and frictionally hold it in place, the entire upper surface of the base being substantially flat and unobstructed by the clamping means except at said rear portion thereof, the said clamping means containing a continuous strip of sheet material having a curled portion remote from and in spaced relation to the base and of substantially spiral formation adapted to retain therein a pencil or similar writing implement, said curled portion extending transversely with respect to the base and being so rolled as to provide a space of gradually decreasing proportions between the spiral-like portion thereof and the adjacent wall of the strip for accommodating and frictionally retaining therein sheets of paper.

2. In a holder of the character described, a base adapted to accommodate thereon a pad, an upwardly extending supporting member joined to the base, and a clamping member carried by the supporting member and adapted for pressing engagement with the rear portion of said pad, at least one of said members being of resilient properties whereby the pad will be yieldably and frictionally held in place between the clamping member and the base, the upper portion of said clamping and supporting members being adjacent each other for accommodating therebetween one or more sheets of paper.

3. A holder of the character described comprising a base adapted to accommodate thereon a pad, a supporting member joined to the base, and a clamping member carried by the supporting member and comprising a continuous strip of resilient sheet material having a lower portion engageable with the rear portion of the base and adapted for yieldable pressing engagement with the rear of the said pad to frictionally hold it in place, the upper portion of the clamping member terminating in a substantially spiral-like portion adapted to retain therein a pencil or other similar writing implement, the supporting member having a portion thereof disposed adjacent the said spiral-like portion of the clamping member and gradually receding therefrom to form a space for accommodating one or more sheets of paper.

4. A holder of the character described containing the combination according to claim 3, the supporting member having a spiral-like portion

remote from the spiral-like portion of the clamping member and being rolled against itself to frictionally accommodate sheets of paper between adjacent walls thereof, the entire upper 5 surface of the base being substantially flat and unobstructed by either of the said members except at the said rear portion thereof.

5. A holder of the character described comprising a base adapted to accommodate thereon a 10 pad, a supporting member associated with and extending upwardly from the rear portion of the base, and a clamping member secured to said supporting member and having a forwardly extending portion engageable with the rear portion 15 of the base and the said pad thereon, at least one of said members being of yieldable construction whereby the pad will be yieldably and frictionally held in place between the clamping member and the base, the lower portions of said 20 clamping and supporting members being in spaced relation and cooperating with the adjacent portion of the base to form therebetween an opening for accommodating a pencil or similar writing implement, the entire upper surface of 25 the base being substantially flat and unobstructed by either of the said members except at the said rear portion thereof.

6. A holder of the character described comprising a base adapted to accommodate thereon a 30 pad, a supporting member joined to and extending upwardly from the rear portion of the base, and a clamping member secured to said supporting member and having a forwardly extending portion engageable with the rear portion 35 of the base and the said pad thereon, at least one of said members being of resilient properties whereby the pad will be yieldably and frictionally held in place between the clamping member and the base, both members containing spiral-like 40 formations remote from each other, each being rolled upon itself to frictionally accommodate sheets of paper between adjacent walls thereof.

7. A holder of the character described containing the combination according to claim 6, 45 each of said spiral-like formations terminating in an internal coiled loop proportioned to accommodate therein a pencil or similar implement, whereby such implements will be retained in place out of engagement with any sheets of paper 50 that are operatively held by this device.

8. A holder of the character described containing the combination according to claim 6, the said spiral-like formations being oppositely disposed, whereby sheets of paper operatively 55 held by one of said formations will be remote from and out of engagement with sheets held by the other formation.

9. A holder of the character described containing the combination according to claim 6, 60 both of said members being formed of continuous strips of resilient sheet material.

10. A holder of the character described comprising a base adapted to accommodate thereon a pad, a supporting member joined to and extending upwardly from the rear portion of the base, and a clamping member secured to said supporting member and comprising a lower forwardly extending portion engageable with the rear portion of the base and the said pad thereon, and an upper portion joined to said supporting member, the forwardly extending portion being of extended proportions and upwardly curved whereby it is adapted to operatively accommodate 70

writing paraphernalia thereon, at least one of said members being of resilient properties, the relative positions and proportions of said members and the base being such as to cause the said lower portion of the clamping member to be in 5 yieldable engagement with the base, the said upper portion of the clamping member and the upper portion of the supporting member being adjacent each other for accommodating there-between sheets of paper. 10

11. A holder of the character described comprising a base adapted to accommodate thereon a pad, a supporting member, adjustable fastening means operatively associated with the base for permitting a vertical adjustment of said member 15 with respect to the base, and a clamping member secured to said supporting member and having a forwardly extending portion engageable with the rear portion of the base and the said pad thereon, at least one of said members being of 20 resilient properties whereby the pad will be yieldably and frictionally held in place between the clamping member and the base.

12. A holder of the character described comprising a base adapted to accommodate thereon a 25 pad, a supporting wall integral with and extending upwardly from the rear of the base, and a yieldable holding element supported by the supporting wall and engageable with the rear portion of the base and the said pad thereon, 30 the juncture between the said wall and the said holding element forming a recess for accommodating writing paraphernalia.

13. A holder of the character described according to claim 12, the juncture of the base and the 35 supporting wall being depressed whereby a space is provided to accommodate a writing implement and whereby an inclination is imparted to the base when the depressed portion and the forward portion of the base are positioned upon a supporting surface. 40

14. A holder of the character described according to claim 12, the supporting wall being forwardly inclined, the holding element being detachably connected to said wall. 45

15. A holder of the character described comprising a base adapted to accommodate thereon a pad, a supporting member joined to and extending upwardly from the base, a clamping member carried by the supporting member and adapted for pressing engagement with the rear portion of the base and the said pad thereon, and means for detachably securing said members together, said means comprising prong elements extending from one of said members and in engagement with the other member, at least one of said members being of resilient properties whereby the pad will be yieldably and frictionally held in place between the clamping member and the base and the clamping member yieldably urged upwardly. 55

16. A holder of the character described comprising a base adapted to accommodate thereon a pad, a supporting member joined to and extending upwardly from the base, and clamping 65 means comprising a plurality of resilient wires carried by the supporting member and adapted for pressing engagement with the rear portion of the base and the said pad thereon, whereby the pad will be yieldably and frictionally held in place between the clamping means and the base. 70

EMANUEL R. POSNACK.
